UNITED STATES PATENT OFFICE.

WILLIAM PARIS BARCLAY, OF CHICAGO, ILLINOIS.

CAR-WHEEL-BALANCING MACHINE.

SPECIFICATION forming part of Letters Patent No. 412,360, dated October 8, 1889.

Application filed September 24, 1888. Serial No. 286,181. (No model.)

To all whom it may concern:

Be it known that I, WILLIAM PARIS BARCLAY, a citizen of the United States, residing at Chicago, in the county of Cook and State of Illinois, have invented a new and useful Car-Wheel-Balancing Machine, of which the following is a specification.

My invention relates to that class of machines constructed for the purpose of indicating the amount that a given body is out of balance when such body is suspended from a revolving center or mandrel. I attain the object by the mechanism illustrated in the accompanying drawings, in which—

Fig. 1 shows a side elevation. Fig. 1½ shows the spring-balance N as viewed from the end of lever K, and in Fig. 2 is shown an end elevation of my balancing-machine. Fig. 3 is a detail view, to an enlarged scale, of the friction-wheels J and L, meshing with each other, and showing the location of a spring t upon the friction-wheel L. Fig. 4 is a longitudinal view in section, to an enlarged scale, of the mandrel E, showing location of friction-wheel J and lever K and sleeve G upon the mandrel when located in the bore of a car-wheel. Fig. 5 shows an end elevation of sleeve G divided in several sections, so that said sections can be expanded when forced up incline part of mandrel E. Fig. 6 is a section view of the small friction-wheel L, showing location of its spring t.

The same letters refer to the same or similar parts throughout the several views.

A is the bed-plate of the machine.

B are the standards, and are secured to the bed-plate by several bolts; or they can be cast all together. The standards B at their top ends have each two circular bearings, into which take the spindles C of the carrying-wheels D. The carrying-wheels D revolve from their spindles C as an axis, and are situated in pairs, one pair with the other, so that the peripheries of said wheels form a revolving bearing for a mandrel or shaft, so that when a shaft or mandrel is situated above and upon the peripheries of the carrying-wheels and turned around the said mandrel or shaft will remain in position upon the peripheries of said carrying-wheels. The mandrel E is made with circular bearings or journal parts

at each end, and the central or middle part of mandrel is tapered for a loose sleeve G to slide upon it in the direction of the length of mandrel. The mandrel E has two oblong holes e', into which a cotter i can be placed or taken out, as desired. The journals or parts e of mandrel E have each a circular hole extending longitudinally through them for the screw-bolts S S to take into, the said bolts extending into their respective places, so that the inner ends of said bolts can be brought to bear against the face of cotter i when the said cotter is placed in either of the oblong holes e'. 65

G is a loose sleeve, made in several sections, as shown in Fig. 5, and is bored tapered to correspond with the central or middle part of mandrel E, and of an exterior diameter to suit the bore of a car-wheel. The middle or central part of sleeve G, as shown in section in Fig. 4, is less in diameter than at the ends of sleeve, and upon the smaller part of sleeve G are placed several rubber rings r, that assist to keep the several sections of sleeve together when it is taken off or placed upon the mandrel E. 75

The plate g of sleeve G is circular, and is secured to the several sections of the sleeve G by several bolts g', that clamp the said plate to one end of the several sections of sleeve G. The bolt-holes in the plate g are made oblong, to admit the several sections of sleeve G to expand or contract, according as the sleeve is moved up or down upon the mandrel E. 85

The circular ring H of the mandrel E has several screw-bolts h, taking into the said ring, the said bolts screwing out or in, so that they can be brought to bear against the ends of the several sections of sleeve G. 90

The friction-wheel J upon the mandrel E supports an arm or lever K, that is secured to the hub of the friction-wheel J by a removable collar j, attached to the hub of friction-wheel. The friction-wheel J, with its attached arm K, can be readily taken off the mandrel, and the friction-wheel J is prevented from turning around in its place upon the mandrel E by a small dowel-pin v, taking into the friction-wheel J and the mandrel E. 100 Attached to the lever K is an eccentric friction-wheel L, that is secured to the said lever

by a bolt or pin riveted to the lever K, and from which the said eccentric friction-wheel is free to turn.

The friction-wheel L has a recess formed upon the face of wheel next to the lever K, and situated in this recess is a small spring t, one end of which takes into the small eccentric friction-wheel and the other end of said spring takes into the lever K. The small eccentric friction-wheel may have several holes bored in it for one of the ends of spring t to take into, so that the eccentric friction-wheel L can be adjusted and the spring t will have sufficient tension to keep the periphery of the small friction-wheel L in contact with the periphery of friction-wheel J.

The friction-wheel L is bored a trifle eccentric, and it is pivoted from the lever K, so that the said friction-wheel will jam with the friction-wheel J when the lever K is moved downward, and when the lever K is moved in the opposite direction the friction-wheel L is free to slide over the periphery of the friction-wheel J, so that the mandrel E is turned around in one direction only during the upward and downward movement of the lever K.

The lever K has a spring-balance N attached to it, the said spring-balance being connected to a pivotal slide n, that can be moved in or out from the center of the mandrel E upon the lever K. The barrel of spring-balance is indexed to indicate the pressure in pounds that the spring of balance is compressed when the knob n' of spring-balance is forced down.

The lever K is shown with two arms, and has a balance-weight attached to its shorter arm, so that the weight W of the longer arm 40 of lever and the weight of the spring-balance can be exactly counterbalanced.

Having described the several parts of the machine, the operation of the same is as follows: A car-wheel or other circular body that requires to be balanced has the hub or central part first bored out, and then is suspended from any convenient tackle above the balancing-machine. The sleeve G is then inserted into the bore of car-wheel, and the mandrel E is afterward inserted into the sleeve. The ring H is subsequently placed over the smaller end of mandrel E, the screws g of ring H coming in contact with the plate g of the sleeve. The cotter i is subsequently inserted into the oblong hole e', situated at the smaller end of mandrel, and the inner end of screw S is brought to bear against the back of cotter i, while the opposite side of cotter i comes in contact with the ring H, so that as the screw S is screwed farther into the end of mandrel it is the means of affecting the cotter i, and through the said cotter the ring H is pressed forward, so that the screws h affect the sleeve G, so that the said sleeve is pressed up 65 the inclined part of mandrel E, and the several sections of sleeve expanded until they are a close and tight fit in the bore of car-

wheel, and hold the same rigid in position upon the sleeve. The ring H and cotter i are used at the opposite end of sleeve, as shown in Figs. 2 and 4, when the sleeve and car-wheel are to be removed from the mandrel. The mandrel can also be forced into the sleeve G, to expand it to the bore of car-wheel, by the blow of a heavy wood mallet, and the mandrel also can be removed from its sleeve in the same manner.

The main object of using the ring H is that by its use the oblong holes e' in the mandrel only require to be a moderate length, the screws h of ring H extending so that they can be adjusted to the position the sleeve occupies upon the mandrel.

The car-wheel or other circular body when secured to the mandrel E by its sleeve is subsequently supported by allowing the journal parts e of mandrel E to rest upon the peripheries of the carrying-wheels D. The knob n' of spring-balance is now acted upon by the hand of the operator to force down the lever K, and at the same time to compress the spring of spring-balance, the compression of the spring indicating the number of pounds of pressure it takes to force the lever K down and turn the mandrel E, with its car-wheel F, around at the position the said lever occupies to the car-wheel. The lever K only requires to be forced downward a short distance at any given point to indicate the number of pounds pressure it takes to move the mandrel E and its attached car-wheel F around, and the difference in pressure at diametrically opposite points, where the greatest and least resistance is shown by the spring-balance to turn the mandrel and car-wheel around, is the amount the car-wheel is out of balance, or heavier upon one diametrically opposite side than the other, and by attaching a weight to the car-wheel equal to the difference in weight between the least and greatest pressures shown by the spring-balance at the point of least resistance where indicated by the spring-balance will equalize the weight of the car-wheel to the amount it is out of balance, so that it will, when revolving, rotate with an equalized force of motion.

As already described, the lever K only moves the car-wheel around in one direction and when the end of lever, with the spring balanced, is lifted up the car-wheel and mandrel remain stationary, and a new position of the lever K to the car-wheel is conveniently acquired, so that the action of the spring-balance to the car-wheel at several different locations can be successively indicated and the car-wheel can be tested as to the amount it is heavier or lighter at any given diametrically-opposite positions.

What I claim, and desire to secure by Letters Patent, is as follows:

1. In a car-wheel-balancing machine, the combination of the standards B, each having a pair of pivotal wheels D, situated so that their peripheries form a revolving bearing

the journals *e*, a mandrel *E*, and a tapered sleeve *G*, adapted to the central inclined part of mandrel *E*, substantially as shown and described.

5 2. In a car-wheel-balancing machine, a mandrel *E* and friction-wheel *J*, combined with movable lever *K*, supporting a pivotal eccentric friction-wheel *L*, with spring *t*, adjusted to hold friction-wheel *L* in contact with friction-wheel *J*, substantially as shown and described.

15 3. In a car-wheel-balancing machine, the combination of the journals *e*, a mandrel *E*, a lever *K*, and a spring-balance *N*, for indicating the resistance or pressure required to move said mandrel in a curvilinear direction when suspended from its journals *e*, substantially as shown and described.

20 4. In a car-wheel-balancing machine, the combination of a mandrel *E*, perforated with oblong holes *e'*, having projecting cotter *i*, the circular ring *H*, adjustable screws *h*, taking over mandrel *E*, and the screw-bolts *S S*, taking into ends of mandrel to attenuate the 25 ring *H* through the cotter *i*, so that sleeve *G* can

be removed or forced up the central inclined part of mandrel, substantially as shown and described.

5 In a car-wheel-balancing machine, the combination of a mandrel *E* and divided sleeve *G* with circular plate *g*, attached by bolts *g'*, and the rubber rings *r*, encircling sleeve *G*, whereby expansion and contraction of said sleeve are permitted with reference to mandrel, substantially as shown and described. 30

6. In a car-wheel-balancing machine, the combination of the standards *B*, provided with pivotal wheels *D*, the mandrel *E*, bearing upon and revolving from peripheries of 40 wheels *D*, and the sleeve *G*, taking onto mandrel *E*, so that a car-wheel can be suspended from its bore and revolved with the mandrel *E*, suspended from the peripheries of carrying-wheels *D*, substantially as shown and described.
